CLAIM

The ornamental design for a folding bed sheet organizer, as shown and described.

DESCRIPTION

FIG. 1 is a perspective view of a folding bed sheet organizer showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is an enlarged view of FIG. 1; and,

FIG. 10 is a front view of the unfolded folding bed sheet organizer.

The broken lines illustrate portions of the folding bed sheet organizer. The dash-dot broken lines indicate an enlarged view. None of the broken lines form part of the claimed design.
